UNITED STATES PATENT OFFICE.

ARTHUR SIMON, OF MILWAUKEE, WISCONSIN, ASSIGNOR TO THE CUTLER-HAMMER MFG. CO., OF MILWAUKEE, WISCONSIN, A CORPORATION OF WISCONSIN.

CIRCUIT-CONTROLLER.

1,378,059.

Specification of Letters Patent. Patented May 17, 1921.

Application filed May 15, 1915. Serial No. 28,406.

To all whom it may concern:

Be it known that I, ARTHUR SIMON, a citizen of the United States, residing at Milwaukee, in the county of Milwaukee and

5 State of Wisconsin, have invented new and useful Improvements in Circuit-Controllers, of which the following is a full, clear, concise, and exact description, reference being had to the accompanying drawing, forming 10 a part of this specification.

This invention relates to improvements in circuit controllers and, while not limited thereto, is particularly applicable to motor controllers.

15 One of the objects of the invention is to provide an improved multiple switch controller wherein the several switches will be positively operated in a definite order, automatically locked in closed position to relieve 20 their operating means from the load thereof and positively moved to open position when released.

A further object is to provide a controller of the aforesaid character wherein the connections 25 between the several switches and their operating means inherently function to lock said switches after closure thereof.

A further object of the invention is to provide a controller with improved means 30 for either power or manual operation thereof.

A further object is to provide a controller with alternative manual and power operating means wherein a single electromagnet 35 serves to control the connection between the controller and the power operating means and also serves as a means to retain the controller in "on" position after either manual or power operation thereof but subject to 40 release upon failure of voltage.

Numerous other objects and advantages of the invention will hereinafter appear.

The invention will now be more specifically described in connection with the accompanying drawings which illustrate one of a number of possible embodiments thereof.

In the drawing,

Figure 1 is a plan view of the controller;

Fig. 2 is an end view thereof;

50 Figs. 3 and 4 are sectional views taken on lines 3 and 4 respectively, Fig. 1; the former showing a switch in open position and the latter showing a switch in closed position;

Fig. 5 is a plan view of a motor drive for 55 the controller;

Fig. 6 is a detail view of a part shown in Fig. 5, and

Fig. 7 is a diagrammatic view showing the controller connected to an electric motor 60 to serve as a starter therefor.

Referring to Fig. 1, the controller comprises in general switch levers 1 to 9 having a common operating shaft 10 provided with operating members 11 to 19, one for 65 each of said levers. Each member acts upon its respective lever through a toggle connection, as hereinafter more specifically set forth, to both open and close the same with a positive action, said toggle connection after 70 operation to close its switch inherently setting to lock the same closed until tripped by reverse movement of its operating member. As illustrated, the members 11 to 19 are so arranged on the shaft 10 as to close the 75 switches 1, 2 and 3 simultaneously and to thereafter close the remaining switches progressively, although it will be understood that said members might be arranged in any other desired manner. The shaft 10 is 80 provided with a return spring 20 and is manually operable against the action of said spring by a hand lever 25, Fig. 1, or by the motor drive, Fig. 5, as will hereinafter be explained. Also, as will be hereinafter set 85 forth, the shaft 10 has associated therewith an electromagnetic clutch for locking the same against reverse rotation under the influence of spring 20 but subject to release at will. 90

All of the switches are of like construction and as illustrated in detail in Figs. 3 and 4, which show switches 2 and 4 respectively. Referring to Fig. 3 the switch lever 2 is fulcrumed in a supporting bracket 30 and carries a laminated brush 31 to bridge stationary contacts 32 and 33 and a pivoted arcing contact 34 to engage a stationary carbon contact 35. Adjacent to its lower end the lever 2 has an outwardly extending 95 lug 36 to which is fulcrumed a pawl 37 of a bell crank form. One arm of the pawl carries a roller 38 to ride on the periphery of member 12 while the other arm of said pawl is connected by a pivoted link 39 with the supporting bracket 30. The parts just described are so arranged as to form a toggle 100 whereby movement of the pawl through en-

gagement of the member 12 and roller 38 positively forces the lever into circuit closing position whereupon the toggle, as shown in Fig. 4, sets to lock the lever against return movement. Such operation of the pawl is effected by a shoulder 40 on the member 12 which upon clockwise rotation of said member, strikes and raises the roller, thereby rotating the pawl counter-clockwise to the position illustrated in Fig. 4, wherein a projection 37^a on the pawl abuts the front face of the switch lever. In this connection it is to be noted that the peripheral surface of the member 12 extending counter-clockwise from the shoulder 40 is of such radius as to clear the roller during continued clockwise rotation of the member 12 whereby said member is relieved of the friction of said roller and in consequence entirely relieved of the load of the switch lever during continued rotation of the shaft 10 to operate the other switch levers. The member 12 also serves upon reverse rotation to break the toggle, this being accomplished by a shoulder 41 on the vertical face of said member to coöperate with a tail piece 42 on the pawl 37. As shown in Fig. 4, the tail piece is projected into the path of the shoulder 41 when the toggle is set so that upon counter-clockwise rotation of the member 12 said shoulder abuts said tail piece and thereby rotates the pawl 37 in a clockwise direction which acts to release the switch lever and also to positively withdraw said lever from circuit-closing position. As above stated, all of the switches are of like construction and provision is thus made for the positive closing, locking and opening of each.

The members 11 to 19 as before stated, are set in different angular positions on the shaft but structurally they are identical except in their manner of attachment to the shaft 10. As illustrated in Figs. 3 and 4, a portion of the shaft 10 is rectangular in cross section while another portion is circular. The rectangular portion of the shaft is provided with an insulating covering 45 and the members 11, 12 and 13 of switches 1, 2 and 3 are secured to this insulated portion of the shaft by suitable clamps 46, the remaining members 14 to 19 being mounted on the circular portion of the shaft and being locked thereto by set screws 47. This particular arrangement of the members on the shaft is provided for a specific use of the controller, as will hereinafter appear.

The shaft is mounted in suitable bearings 50 and 51 and has extensions beyond both bearings. The operating lever 25 is revolvably mounted upon the left hand extension of the shaft 10 and is arranged to rotate said shaft and the cams thereon in a direction for closure of the several switches by abutment with a stop 52 fixed to said shaft 65 and projecting into the path of said lever.

The lever is mounted in this manner so that it may remain stationary when the controller is operated by power. However, it will be apparent that if desired the lever might be fixed to the shaft. Also for control of the 70 electrical means hereinafter described, the lever has associated therewith a pair of contact clips 53 and 54 which it bridges in its "down" position and a pair of contact clips 55, 56 which it bridges in its "up" 75 position, while the extreme left hand end of the shaft 10 has fixed thereto drum segments 57 and 58 coöoperating with stationary contact fingers 59 and 60 respectively. The drum segments are electrically connected 80 and are so arranged as to engage their respective fingers except in the one angular position of the shaft representing closure of all of the switch levers.

Referring now to Figs. 1 and 6 the return spring 20 for shaft 10 is coiled about said shaft and has its inner end fixed thereto while its outer end is secured by a bolt 61 to the bearing 51. Also, it will be noted, that the spring is coiled in a direction 90 whereby it will act to rotate shaft 10 and the cams thereon in a direction for opening of the several switches.

Referring now to Fig. 5, the power driving mechanism comprises an electric motor 95 70 driving through a suitable coupling 71 into a worm gear set 72 and thence through a mechanical clutch 73 to a pinion 74 meshing with a double pinion 75, in turn meshing with a pinion 76 on the right hand extension of controller shaft 10. The mechanical clutch 73 thus serves to couple and uncouple the motor and controller at will. Moreover, the clutch being interposed between the controller shaft and the worm gear set 72 serves as a means to releasably lock the shaft 10 against rotation by the spring 20, it being understood that when the clutch is set and the motor inert the worm gear locks the clutch member associated therewith against rotation. The clutch is controllable by a lever 77 biased by a tension device 78 to disengage the clutch members and said lever is provided with an operating solenoid 79 for effecting movement 115 thereof to engage the clutch members.

Referring now to Fig. 7, the controller is shown as employed for starting an alternating current motor M. The switch levers 1, 2 and 3 control the primary circuit of the 120 motor and to provide proper insulation between the same the cams 11, 12 and 13 are mounted on the insulated section of the shaft 10 as heretofore set forth, while the switches 4 to 9 respectively control resistances r^4 to r^9 125 in the secondary circuit of the motor.

The driving motor 70 for the controller and the solenoid 79 are directly connected to one line of the supply circuit $l-l'-l^2$ and are connected to another line of said circuit 130

through the contacts 53—54 associated with the operating lever 25 and a pilot switch 80, the circuit of the motor also extending through the drum segments 57—58 on the controller shaft. Further, an alternative circuit for the clutch solenoid 79 extends through the contacts 55—56 associated with the operating lever 25. In this connection it will be noted that energization of solenoid 79 is dependent upon the voltage of the supply circuit and hence will be deenergized upon failure of such voltage.

More specifically the arrangement is such that with the lever 25 in down position closure of switch 80 completes circuit from line l' of the supply circuit by conductor 85 through said switch 80, by conductor 86 through the contacts 53—54 at which point the circuit divides, one branch extending by conductor 87 through the drum segments 57—58 by conductor 88 through the motor 70, by conductor 89 to line l of the supply circuit, while the other branch extends by conductor 90 through the clutch solenoid 79 to conductor 89 and thence to line l . Hence closure of switch 80 under these conditions couples the motor 70 to the shaft 10 and sets said motor in operation whereupon the controller is operated automatically. Upon completion of such operation the drum segments 57—58 disengage their respective contact fingers thereby interrupting the circuit of motor 70 while the solenoid 79 remains energized to maintain the controller in running position. When it is desired to stop the motor M then the switch 80 is opened to deenergize solenoid 79 thereby releasing the clutch and the controller shaft 10 to permit the latter to operate under the influence of the spring 20. Such operation of the shaft, as above set forth, effects positive opening of all of the switch levers.

For manual operation the switch 80 is allowed to remain open whereby the controller is maintained free of the motor driving mechanism and hence is readily operable by the lever 25. When, however, the controller is fully operated, lever 25 bridges contacts 55—56 thereby completing circuit from line l' by conductors 85 and 91 through said contacts, by conductors 92 and 90 through the clutch solenoid to conductor 89 and line l thereby energizing said solenoid to set the clutch. This again locks the controller shaft and, under such conditions, release of the controller shaft for return of the controller to off position is effected by withdrawal of the lever 25 from the contact clips 55—56, which deenergizes the solenoid 79 with the results aforesaid.

It will thus be apparent that the means described provides for readily shifting the control of the device to either the operating lever or to the motor driving mechanism as desired, and provides for control of the elec-

trical means in a very simple and convenient manner, at the same time utilizing the solenoid 79 for the double function above described. Also it will be apparent that should the line voltage fail during operation of the controller or subsequently, solenoid 79 would release the clutch and thereby release the controller for automatic return to "off" position.

What I claim as new and desire to secure by Letters Patent is:—

1. In combination, a pivoted switch member biased to open position, an arm pivoted thereto and extending outwardly therefrom, a link element having one end pivotally connected to the outer end of said arm and its opposite end pivoted at a fixed point, said arm being normally disposed at an acute angle to said link element and being movable through a position wherein its pivot points are in alinement with the pivot points of the latter to move said switch member into closed position with a toggle action and to lock the same therein, and a cam operable to move said arm in opposite directions to effect opening and closing movements of said switch member.

2. In combination, a pivoted switch member biased to open position, a lever pivoted thereto and having a plurality of arms extending outwardly therefrom, a link element having one end pivotally connected to the outer end of one of said arms and its opposite end pivoted at a fixed point, said arm being disposed at an acute angle to said link element and being movable through a position wherein its pivot points are in alinement with the pivot points of the latter to move said switch member into closed position with a toggle action and to lock the same therein, and a rotatable cam member associated with the other arm of said lever to move the same in opposite directions to open and to close said switch member.

3. In combination, a pivoted switch member biased to open position, a lever pivoted thereto and having a plurality of arms extending outwardly therefrom, and a link element having one end pivotally connected to the outer end of one of said arms and its opposite end pivoted at a fixed point, said arm being disposed at an acute angle to said link element and being movable through a position wherein its pivot points are in alinement with the pivot points of the latter to move said switch member into closed position and to lock the same therein and a rotatable cam having a radial projection to act upon the other arm of said lever to move the same in one direction for closure of said switch member and an axial projection for engaging said latter arm to move the same in an opposite direction for opening of said switch member.

4. In a circuit controller, in combination,

a plurality of pivoted switch members, a link and lever mechanism associated with each for moving the same to closed position with a toggle action and for locking the same therein, said mechanisms each including an arm pivoted to its respective switch member and extending outwardly therefrom and a link element disposed at an acute angle to said arm and having one end pivoted to the outer end thereof and its opposite end pivoted at a fixed point and an operating member common to said switch members and having a plurality of shouldered members to move the arms of said mechanisms in opposite directions in a definite sequence for closing and for releasing of said switch members.

5. In a circuit controller, in combination, a plurality of pivoted switch members, a link and lever mechanism associated with each for moving the same to closed position with a toggle action and for locking the same therein, said mechanisms each including a plurality of pivotally connected members, certain of the same being pivoted at a fixed point and another being pivoted to its respective switch arm and having a depending lug and an operating member common to said switch arms and having a plurality 25 of shouldered members to actuate the depending lugs of said mechanisms for positive closing and release of said switch arms, said projections being disposed to act upon the lugs of said mechanisms in a definite order 30 and to disengage each after closure of the switch arm associated therewith.

6. In combination, a circuit controller biased to a predetermined position, alternative manual and power operating means 40 therefor, and electro-responsive means functioning to control the connection between said power-operating means and said circuit controller and to releasably lock said controller against return movement after 45 operation by either said manual or power means.

7. In combination, a circuit controller biased to a predetermined position, alternative manual and power operating means for said controller and an electro-magnetically controlled device for coupling said controller to said power operating means for operation thereof and for restraining said controller against its biased movement after operation by either said manual or power operating means.

8. In combination, a circuit controller biased to a predetermined position, alternative manual and power operating means for said controller and an electro-magnetically controlled device for coupling said controller to said power operating means for operation thereof and for restraining said controller against its biased movement after operation by either said manual or power operating means but subject to release of said controller upon failure of line voltage.

9. In combination, a circuit controller biased to circuit breaking position, power operating means for said controller, an electro-magnetically controlled coupling between said controller and said means and manual operating means for said controller governing said electro-magnetically controlled coupling to lock said controller in circuit making position subject to release at will.

10. In combination, a circuit controller biased to circuit breaking position, power operating means for said controller, an electro-magnetically controlled coupling between said controller and said means and manual operating means for said controller governing said electro-magnetically controlled coupling to lock said controller in circuit making position subject to release at will, said electro-magnetically controlled coupling being subject to release upon failure of line voltage.

In witness whereof, I have hereunto subscribed my name.

ARTHUR SIMON.
